UNITED STATES PATENT OFFICE

RAYMOND A. WALTER, OF NEW YORK, N. Y., ASSIGNOR TO CONVEYOR SALES COMPANY, OF NEW YORK, N. Y., A CORPORATION OF NEW YORK

COMBINATION ELEVATOR AND CONVEYER

Application filed March 16, 1927. Serial No. 175,794.

This invention relates in general to transport mechanisms and more particularly has reference to a combination elevator conveyer.

Previous to this time there has not been provided any mechanism adapted to transport material from various points or from one elevation to another where the points of loading and the points of discharge are continuously changing in their relation to each other.

An object of this invention is to provide a combination elevator and conveyer adapted to transport material from various points.

Another object of this invention is to provide a combination elevator and conveyer adapted to transport material from one elevation to another.

A further object of this invention is to provide a combination elevator and conveyer adapted to transport material from various points, or from one elevation to another where the points of loading and the points of discharge are continuously changing in their relation to each other.

This invention consists in general of the provision of a transport device comprising a series of interchangeable units which may be combined to form various combinations of conveyers and elevators of any desired length.

With these and other objects in view which may be incident to my improvements, the invention consists in the parts and combinations to be hereinafter set forth and claimed, with the understanding that the several necessary elements comprising my invention, may be varied in construction, proportions and arrangement, without departing from the spirit and scope of the appended claims.

In order to make my invention more clearly understood, I have shown in the accompanying drawings means for carrying the same into practical effect, without limiting the improvements in their useful applications to the particular constructions, which for the purpose of explanation, have been made the subject of illustration.

In the drawings:

Figure 1 is a top plan view of the combination conveyer and elevator;

Fig. 2 is a side elevational view of the combination conveyer and elevator functioning as an elevator;

Fig. 3 is a side elevational view of the combination conveyer and elevator functioning as a conveyer;

Fig. 4 is a side elevation fragmentary view of discharge section of the combination elevator and conveyer.

Figure 5 is an elevational view showing one end of conveyer section from the inside.

Figure 6 is an elevational view showing an adjacent end of conveyer section.

Fig. 7 is a sectional view taken on line 5—5 of Figure 4;

Fig. 8 is a front view of the discharge section.

Referring by numerals to the drawings, wherein like symbols of reference refer to similar elements throughout and more particularly to Figure 1, the combination elevator and conveyer comprises a driving or discharging section 1, a power section 2, a return section 3, and a body or filler section 4.

The various sections comprising the combination elevator and conveyer are joined by a connection 5, illustrated in greater detail in Figures 4, 5 and 6 to be hereinafter more fully described. The sides of the sections forming the conveyer frame are made up of oppositely disposed aligned channel irons 6 and 7 as shown in Figure 7. A plate 11 is centrally fixed to the inner surfaces of the channel irons 6 and 7 and fastened by angle irons 13 and 14 or by any other suitable means.

The ends of a shaft 15 are journaled in the frame on the end of the discharging section 1, as shown in Figure 8, and held therein by collars 16 and 17. A sprocket wheel 18 is keyed to the end of the shaft projecting through the collar 16. There are also keyed on the shaft, sprocket wheels 19 and 21.

The ends of a shaft 22 are journaled in the end of the frame on the return section 3, as shown in Figure 1, and held by collars 23 and 24. There are also mounted on the shaft, sprocket wheels 25 and 26 in alignment with the sprocket wheels 19 and 21 keyed on the shaft 15.

The power section 2 is mounted on a base 27 together with a motor 28. The motor 28 may be of any desired type deemed most suitable for the particular requirements and 5 may be located at any point desired as it is manifest that a particular mounting of the source of power is in no wise a necessary feature of this invention.

The motor 28 is provided with a drive 10 shaft 29 having keyed thereon a sprocket wheel 31. Mounted parallel to the drive shaft 29 of the motor is a shaft 32 supported by standards 33 mounted on the base 27. A 15 sprocket wheel 34 is keyed on one end of the shaft 32 and another sprocket 35 is keyed on the other end, as shown in Figure 1.

The adjacent sections of the mechanism are joined by a connection 5, better shown in Figure 4 wherein the longitudinal sections 20 through the open joint shown in Figures 5 and 6 show the details of the connection.

A splice plate 36 formed as a channel iron is riveted to the section 4 or secured by any 25 other suitable means through apertures 37. The other end of the splice plate 36 is provided with apertures 38 adapted to coincide with slotted apertures 39 bored in the end of the adjacent section 1, and secured thereto 30 by bolts 41. The slotted form of the apertures 39 permits longitudinal adjustment of the sections.

Plates 42 are fixed to the top and bottom of the channel irons forming the frame on one 35 end of each section to be joined and the adjacent section is slipped in between the plates. A plurality of blocks 43 are mounted on each section between the opposite ends of the plates 42 and fixed therein by bolts 44.

40 The connection is tightened after two adjacent sections have been properly drawn in position by takeup bolts 45 having heads 46 and nuts 47 extending through the blocks 43.

The plates 11 of the adjacent sections are 45 beveled at their ends so that, when two sections are drawn together by the bolts 45 and fixed in place by the bolts 41, a smooth running surface will be presented. A supplementary plate 48 is fastened beneath the 50 beveled connections of the plate 11 to prevent leakage at these points.

Flanges 51 are mounted on the top of the frame to prevent spillage of material during operation. At the point of juncture of 55 adjacent sections a supplementary flange 52, having an indented bottom portion, is inserted to clear the top plate 42 forming the connection 5 and engage the flange on the adjacent section. The flanges may be dispensed with if so desired.

A flexible transmission mechanism 53, such as a steel chain, comprising links 54 and rollers 55, is adapted to engage the aligned sprockets 19 and 21 keyed on the shaft 11 65 on the forward section 1, and the sprockets

25 and 26 keyed on the shaft 22 on the return section 3. Transverse cross flights 56, having end portions 57, are mounted on the chain 53, adapted to slide on the plate 11. The cross flights 56 are suitably spaced to afford 70 the greatest utility for the particular material being conveyed.

A suitable flexible transmission mechanism such as a chain 58 is adapted to cooperate 75 with the sprocket wheel 31 keyed on the shaft 29 on the prime mover 28, and the sprocket wheel 34 keyed on the shaft 32 on the driving section 2, as shown in Figure 2. A like chain 59 is adapted to cooperate with the sprocket wheel 35 keyed on the opposite end of the 80 shaft 32 and the sprocket wheel 18 keyed on the shaft 15 in the end of the frame on the forward portion 1.

The prime mover 28, through this series 85 of sprockets and chains, is adapted to operate the head shaft 15 and the driving sprockets 19 and 21 keyed on the shaft, which in turn operate the chain belts 53 rotating on the sprockets 25 and 26 keyed on the shaft 22, thus operating the cross flights 56 and 90 affording forward or backward carriage of any material deposited on the plate 11.

The chains 53 are adapted to be detachable or separable at suitable points so that they 95 may be lengthened or shortened to accommodate the sections 1, 2 and 3 and the total of body sections 4 employed to make up a complete unit. The chain 59 is also separable and extensible or retractable so that it may be adjusted to suit any desired distance between the sprockets 18 and 35 according to the number of body sections 4 used.

The operation of this invention may be 100 readily understood having reference to Figures 2 and 3. The form of the mechanism is 105 dependent upon the position of the body or filler sections 4 with respect to the driving and discharge sections 1 and 2. When the section 4 is inserted between the sections 1 and 2 the assembled unit is adapted to function as an elevator, as shown in Figure 2, to elevate material to a car 61 or any other receptacle, or if it is desired that the mechanism serve for longitudinal transport, the sections 4 are inserted between the power section 110 2 and the return section 3, and assembled in this form functions primarily as a conveyor with only a slight elevation at the end where the material transported may be discharged into a chute 62 or any suitable 115 conveyor.

It is apparent that the assembled unit may be extended by inserting additional sections 4 up to the limit of the power of the prime mover 28 and the resistance of the chains 53 120 forming the conveying or elevating drive.

There is accomplished by this invention a combination elevator and conveyor having a series of separable interchangeable units adapted to be combined to form various com- 125

binations of conveyers and elevators to afford efficient transport for materials where the point of loading and the point of discharging are continuously changing in their relation to each other.

5 While I have shown and described the preferred embodiment of my invention, I wish it to be understood that I do not confine myself to the precise details of construction herein set forth, by way of illustration, as 10 it is apparent that many changes and variations may be made therein, by those skilled in the art, without departing from the spirit of the invention, or exceeding the scope of 15 the appended claims.

I claim:

20 1. An apparatus of the class described comprising a plurality of detachable sections having different shapes capable of arrangement to change the amount of the inclined portions, means to join the sections to form a frame for conveying and elevating material and means to move material placed on the frame thereover.

25 2. An apparatus of the class described comprising a plurality of detachable sections having different shapes capable of arrangement to change the amount of the inclined portions, means to join the sections to 30 form a frame for conveying and elevating material, flexible driving mechanism mounted on each side of the frame and means transversely mounted with respect to the frame carried by said flexible driving mechanism 35 to move material over the frame.

35 3. An apparatus of the class described comprising a power section, a driving section, a return section, and a body section, said sections having different shapes capable 40 of rearrangement to change the amount of the inclined portions, means positioned at the ends of each section for attaching same to the adjacent section to form a frame to convey and elevate material, a flexible driving 45 mechanism mounted on each side of the frame, means associated with the power section to actuate the flexible driving mechanism and means transversely mounted with respect to said frame and carried by said 50 flexible driving mechanism to move material over the frame.

45 4. An apparatus of the class described comprising a plurality of detachable sections having different shapes capable of rearrangement to change the amount of the inclined portions, a splice plate secured to one 55 end of each of the adjacent sections and provided with apertures, the end of the adjacent section to which the splice plate is to be attached having slotted apertures, means for connecting said adjacent sections and means to tighten the adjacent sections to form a 60 continuous frame for elevating and conveying material.

55 5. An apparatus of the class described

comprising a plurality of detachable sections having different shapes capable of rearrangement to change the amount of the inclined portions, a splice plate secured to one end of each of the adjacent sections and provided 70 with apertures, the end of the adjacent section to which the splice plate is to be attached having slotted apertures, means for connecting said adjacent sections, means to tighten the adjacent sections to form a continuous 75 frame for elevating and conveying material and means to move material placed on the frame thereover.

6. An apparatus of the class described comprising a plurality of detachable sections having different shapes capable of rearrangement to change the amount of the inclined portions, a splice plate secured to one end of each of the adjacent sections and provided 80 with apertures, the end of the adjacent section to which the splice plate is to be attached having slotted apertures, means for connecting said adjacent sections, means to tighten the adjacent sections to form a continuous 85 frame for elevating and conveying material, flexible driving mechanism mounted on each side of the frame and means transversely mounted with respect to the frame carried by said flexible driving mechanism to move material over the frame.

In testimony whereof I affix my signature.
RAYMOND A. WALTER.
